UNITED STATES PATENT OFFICE.

JOSEPH J. HERNDON, OF NEWKIRK, OKLAHOMA TERRITORY, ASSIGNOR OF ONE-HALF TO
ABNER C. HARRINGTON, OF NEWKIRK, OKLAHOMA TERRITORY.

RAIL-JOINT.

No. 867,657.

Specification of Letters Patent.

Patented Oct. 8, 1907.

Application filed January 28, 1907. Serial No. 354,524.

To all whom it may concern:

Be it known that I, JOSEPH J. HERNDON, a citizen of the United States, residing at Newkirk, in the county of Kay and Territory of Oklahoma, have invented 5 certain new and useful Improvements in Rail-Joints, of which the following is a specification.

This invention has for its object an improved construction of rail joint which will securely hold the two abutting ends of rails together and in proper alinement 10 without the expense and weakening effect of drilling holes in the rails, which may be easily applied and removed so as to replace an old rail with a new one, without removing the spikes that hold the chair to the ties, which will be cheap to manufacture and therefore 15 be economical in use, and which will be durable and efficient.

With this and other objects in view, as will more fully appear as the description proceeds, the invention consists in certain constructions and combinations of 20 the parts hereinafter described and claimed.

For a full description of the invention and the merits thereof and also to acquire a knowledge of the details of construction of the means for effecting the result, reference is to be had to the following description and 25 accompanying drawings, in which:

Figure 1 is a perspective view illustrating the application of my improved rail joint; Fig. 2 is a transverse sectional view; and, Fig. 3 is a detail perspective view of the chair detached.

30 Corresponding and like parts are referred to in the following description and indicated in all the views of the drawings by the same reference characters.

Referring to the drawing, the numerals 1 and 2 designate the abutting ends of two rails and 3 the base 35 plate of my improved chair. The said base plate extends across the lower face of the base of both rails and is provided at one side with a preferably integral plate 4 which extends upwardly and inwardly over one base flange of the rails, the said chair being provided at its 40 edge with two or more notches to receive the spikes for holding this side edge of the device to the ties.

Coacting with the integral plate 4 is a removable

plate 5 which is adapted to extend up over the opposite base flange of the rails, preferably into engagement with the web of the rails, and the said removable plate 45 5 is preferably provided with two or more lugs 6 adapted to fit into sockets 7 in the said base flange of the rails. Bolts 8 extend upwardly through the base plate 3 of the chair and through the removable plate 5, and nuts 9 work on said bolts and secure the removable 50 plate 5 to the base plate 3, as shown. The said nuts 9 are preferably locked and held from working loose by means of a lock-bar 10 which is forked at its ends, as shown, to fit securely down over the nuts. The base plate 3 is provided near its outer edge with two 55 or more openings for the reception of spikes, as shown.

From the foregoing description in connection with the accompanying drawing, it will be seen that my improved rail joint may be readily applied to the ends of the rails and that an old rail may be readily taken 60 out and replaced by a new one whenever desired. It is never necessary in this operation of replacing an old rail by a new one, to remove the spikes which hold the chair to the ties, as it is only necessary to first remove the lock-bar 10 and unscrew the nuts 9 and remove 65 the removable plate 5, whereupon it is manifest that the rails may be slid outwardly from engagement with the permanent or integral plate 4 of the chair.

Having thus described the invention, what is claimed as new is:

The combination with the two abutting ends of rails, of a chair consisting of a base plate adapted to extend under the rails and provided with an integral plate adapted to extend up over one base flange of the rails, a removable plate adapted to extend over the opposite base 75 flange, bolts extending through the base plate and through the removable plate whereby to secure the said removable plate in place, said bolts being provided with nuts on their upper ends, and a lock-bar provided with forked ends fitted over said nuts.

In testimony whereof I affix my signature in presence of two witnesses.

JOSEPH J. HERNDON. [L. S.]
